UNITED STATES PATENT OFFICE.

EDWIN L. BRADFORD, OF TAKOMA PARK, AND GILBERT P. RITTER, OF WASHINGTON, DISTRICT OF COLUMBIA, ASSIGNORS TO THE McCONWAY & TORLEY COMPANY, OF PITTSBURGH, PENNSYLVANIA, A CORPORATION OF PENNSYLVANIA.

DRAFT APPLIANCE FOR RAILWAY-VEHICLES.

1,234,617.

Specification of Letters Patent. Patented July 24, 1917.

Application filed July 22, 1915. Serial No. 41,307.

To all whom it may concern:

Be it known that we, EDWIN L. BRADFORD and GILBERT P. RITTER, citizens of the United States, residing, respectively, at Takoma Park, in the District of Columbia, and at Washington, in the District of Columbia, have invented certain new and useful Improvements in Draft Appliances for Railway-Vehicles; and we do hereby declare the following to be a full, clear, and exact description of the invention, such as will enable others skilled in the art to which it appertains to make and use the same.

Our invention relates to the construction of draft appliances for railway vehicles and is designed to afford simple, durable and efficient means for centralizing the stem of a laterally movable coupler with respect to the vehicle upon which it is mounted and, in case the head of the coupler is pivotally mounted upon the stem thereof, to also afford means for centralizing said head with respect to the stem.

A further object of the invention is to so form and combine the several elements constituting the mechanism as to render it easy to assemble and disassemble the parts, thus facilitating the making of repairs when any may be required.

Although, as will hereinafter appear and be particularly pointed out in the claims, there are various elemental combinations contributing to the accomplishment of the objects mentioned, such objects, generally stated, may be said to be effected by combining with a laterally movable coupler stem the following instrumentalities mounted on said stem in an orderly arrangement from front to rear, namely, a pivoted coupler head, a reciprocating follower, a spring, another follower, and a lever device. This arrangement of devices results in the production of a simple form of mechanism the parts of which may be assembled and disassembled without the use of special tools and without the necessity of cutting any rivets.

In the drawings illustrating the invention, the scope whereof is pointed out in the claims,

Figure 1 is a side elevation of a car cou-

pler provided with centralizing mechanism constructed in accordance with the invention, a portion of the coupler head being broken away.

Fig. 2 is a plan view of the devices illustrated in Fig. 1, a portion of the stem of the coupler being broken away, the coupler head being in horizontal section and the parts being in normal position.

Fig. 3 is a horizontal central section of the devices illustrated in Figs. 1 and 2, the lever device by which the spring is operated when the coupler stem is displaced laterally being shown in plan and the several parts being illustrated in the positions they occupy when the railway vehicle is passing around a curve.

Fig. 4 is a longitudinal vertical section of the mechanism.

Fig. 5 is a vertical section, taken on the line 5—5, Fig. 2.

Fig. 6 is a view of another form of our invention, the coupler head being in horizontal section, the upper plate or branch of the coupler stem being removed, and the remaining parts being shown in plan in their normal positions;

Fig. 7 is a detail side elevation of a portion of the mechanism illustrated in Fig. 6.

In the drawings, 1 indicates the stem of a coupler and 2 is the coupler head. The head is preferably connected to the stem 1 by means of a pivot pin 3, and the stem 1 is preferably formed with similar upper and lower plates or branches 4 which are united at their rear ends. As a convenient means for pivotally connecting the coupler to a car the rear end of the stem 1 may be provided with a pivot pin opening 5 which is adapted to receive the usual tail pin (not shown) whereby the coupler may be attached to the draft rigging devices.

Upon the stem 1 of the coupler are slidably mounted a follower 6 and another follower 7. Between these followers a spring 8 is interposed. The forward follower 6 is designed to be forced rearwardly to cause a compression of the longitudinally extending spring 8 when the coupler head 2 is rotated on the pivot pin 3 in either direction from its normal position. To this end such

follower 6 is preferably formed with laterally disposed forwardly extending arms or portions 9 which terminate at their outer ends in vertically extending faces which are adapted to coöperate with corresponding vertically extending shoulders 10 that are formed upon the interior of the coupler head.

The rear follower 7 is moved forwardly 10 to cause a compression of the spring 8 when the coupler stem 1 is displaced laterally from its normal position. This movement of the follower 7 is preferably effected by a lever device 11 which though it may be made 15 integral is in effect a plurality of levers since it is provided with a plurality of fulcrum points 12 which are adapted to respectively coöperate with corresponding laterally spaced fulcrum points 13 upon the coupler stem. The fulcrum points 12 are preferably formed as curved seats or recesses, while the fulcrum points 13 of the stem are preferably convexly curved projections at the forward end of the fulcrum member or 20 spacer 14 which is secured between the plates or bars 4 of the coupler stem toward the rear end thereof by means of rivets 15. The lever device 11 is fashioned with forwardly extending arms 16 which respectively project laterally from opposite sides of the coupler stem and whose extremities are adapted 25 to engage a carry iron 17 or other abutment carried by the railway vehicle. In order to permit the follower 7 to move rectilinearly 30 during the turning movements of the lever device 11 upon either of its fulcrum points, said lever device and follower are arranged to rock upon each other. This rocking movement may be conveniently provided for 35 by forming the lever device 11 at a point intermediate of its fulcrum with vertically extending pintles 18 which are adapted to enter corresponding seats or recesses 19 at the rear ends of the upper end lower plate-like 40 extensions or guides 20 with which the follower 7 is preferably provided.

It is preferred to so construct the mechanism that one of the followers may engage and serve to guide the other during its reciprocations with respect to the coupler stem. In the form of construction illustrated in Figs. 1 to 5, inclusive, of the drawings, the follower 6 is designed to guide the follower 7. To this end the follower 6 is 50 provided with guiding means which instead of passing through the spring 8 are formed as rearwardly extending bars 21 which overlappingly engage the lateral edges of the upper and lower plates or branches 4 of the coupler stem as well as the lateral edges of the plate-like extensions 20 of the rear follower 7. At their rear ends the upper guiding bars or flanges 21 are preferably connected in a transverse direction by a bar 22, 60 and the rear ends of the lower guiding bars 65

or flanges 21 are similarly connected by another bar 22. The bars 22 pass transversely across the coupler stem 1 to the rear of the lever device 11, the forward end of the spacing member or fulcrum block 14 being recessed on its upper and lower faces, as indicated at 23 in order to afford clearance for the movement of said bars when the follower 6 reciprocates.

In order to permit the lever device 11 to 75 be brought into assembled position with respect to the followers 6 and 7, the guide members 21 of the forward follower are formed near their rear ends with openings 24 which are adapted to permit the passage 80 of the pintles 18 of the lever device.

In the construction illustrated in Figs. 6 and 7 each of the followers is independently guided by engaging the plates or branches 4 of the coupler stem 1. In this form of 85 construction the spring 8 is interposed between a forward follower 25 and a rear follower 26. The forward follower is provided with arms 9 corresponding in form and function to the arms 9 of the follower 6, but instead of having guiding bars or flanges 21 which have overlapping engagement with the follower 26, said follower 25 is provided with comparatively short guiding bars or flanges 27 which have overlapping engagement 90 with the lateral edges of the coupler stem plates 4 only. As shown in Fig. 6, the inner faces of the guides 27 may be formed with longitudinally extending ribs 28 which, by engaging the plates 4, serve to prevent 100 any vertical twisting movement of the forward follower. The rear follower 26 is substantially identical in construction to the follower 7 except that it is provided upon each side with vertically extending guide 105 flanges 29 which have overlapping engagement with the lateral edges of the plates or bars 4 of the coupler. As the guiding bars 27 have no transverse connections overlapping the filler member or fulcrum block 30, 110 the forward end of the latter need not be recessed but may extend vertically the full distance between the opposed faces of the plates or branches 4 of the coupler stem. The lever device 11 may be of the same form 115 as that employed in the form of construction heretofore described. Except for the differences that have been particularly noted the features of construction illustrated in Figs. 6 and 7 are the same as those shown 120 in Figs. 1 to 5, inclusive, and, accordingly, the corresponding structural features in both forms of the invention have been indicated by corresponding reference characters.

The mechanism shown in Figs. 1 to 5, inclusive, for centralizing the coupler stem and the coupler as a whole, as well as for centralizing the coupler head with respect to the stem, may be assembled as follows: The lever device 11 is inserted transversely 125

between the rearwardly extending portions 21 of the follower member 6, the pintles 18 passing through the corresponding openings 24. The rear follower 7 is then placed in position and brought into engagement with the pintles upon the lever device, after which the spring 8 is inserted. As thus assembled these devices are inserted between the upper and lower plates or branches 4 of the coupler stem and are slid rearwardly until the fulcrum points 12 of the lever device engage the corresponding fulcrum points 13 on the fulcrum block or filler member 14. The coupler head 2 is then placed in position and the pivot pin 3 is passed through the apertures in said head and the apertures in the forward ends of the plates 4, the spring 8 being compressed slightly. In assembling the construction shown in Figs. 6 and 7, the lever device 11 is placed in position on the coupler stem, the rear follower 26 is entered between the branches 4 of the stem and slid rearwardly, the spring 8 is next placed in position and the forward follower 25 is entered between the branches of the coupler stem and moved rearwardly thereon. The coupler head 2 may then be applied to the coupler stem 1 and secured thereto by means of the pivot pin 3. It will be noted that both forms of the invention are highly advantageous in that either may be assembled or disassembled without the necessity of using special tools or cutting any rivets.

The mode of operation, of both forms of the invention will be readily understood from a description of the operation of one form. Assuming the parts to be in normal position, the coupler stem being in the longitudinal axis of the railway vehicle and the coupler head being centralized with respect to the stem, the passage of the vehicle around a curve will cause the coupler stem 1 to be displaced laterally from its normal position. As the levers or lever arms 16 of the lever device 11 are in contact or substantially in contact with the inner faces of the carry iron or abutments 17 carried by the vehicle, the lateral displacement of the coupler stem causes the lever device to rotate with respect to said stem upon one or the other pair of fulcrum points 12 and 13, thus causing the rear follower 7 to move forwardly and compress the spring 8 between it and the forward follower 6. When the force causing the displacement of the coupler stem from normal position ceases to act, the subsequent expansion of the spring 8 restores the several parts of the mechanism to normal position, thus returning the coupler stem to a central position. When the coupler head 2 turns upon the pivot pin 3 with respect to the coupler stem 1, one or the other of the vertically extending shoulders 10 upon said head remains in engage-

ment with the outer end of the adjacent projection or extension 9 of the follower 6, thus causing the latter to move rearwardly and compress the spring 8 against the rear follower 7. The subsequent expansion of the spring 8 returns the follower 6 to normal position, thus rotating the coupler head 2 until it is centralized with respect to the coupler stem. While these operations of the centralizing mechanism have been separately described, it is to be understood that they may, and usually do, occur simultaneously.

We claim:

1. In a draft appliance for railway vehicles, the combination with a laterally swinging coupler having a head and stem, of a lever device mounted on said stem and adapted to have a turning movement with respect thereto, and a spring mounted on said stem and adapted to be energized by said lever device, said spring being disposed in the direction of length of said stem and being located between said lever device and said head. 80

2. In a draft appliance for railway vehicles, the combination with a laterally swinging coupler having a head and stem, of a lever device which is adapted to turn with respect to said stem and which is provided with a plurality of spaced fulcra, and a spring which is adapted to be energized by said lever device, said stem being provided with a plurality of laterally spaced fulcra which are adapted to coöperate with the corresponding fulcra of said lever device, and said spring when the lever device is displaced from normal position being adapted to exert pressure upon said lever device at a point between the then acting fulcrum and the point of application to the lever device of the force causing the displacement of said device. 95

3. In a draft appliance for railway vehicles, the combination with a laterally swinging coupler, of a lever device which is movable with respect to said coupler, and yielding means acting upon said lever device, said lever device having a plurality of fulcra, one of said fulcra being active and the other being inactive when the coupler is displaced laterally from normal position, and the inactive fulcrum being between the active fulcrum and the point of application to the lever device of the force causing the displacement of said lever device from normal position. 110

4. In a draft appliance for railway vehicles, the combination with a laterally swinging coupler having a head and stem, of a lever device mounted on said stem and adapted to have a turning movement with respect to said stem, and yielding means which are energized by the displacement of said lever device from normal position, said 125

lever device having a plurality of fulcra and a plurality of arms projecting laterally from said stem and extending from said fulcra forwardly toward the coupler head, said lever device being adapted to be actuated through either of said arms, and said yielding means being operatively connected to said lever device between the fulcra thereof.

5. In a draft appliance for railway vehicles, the combination with a laterally swinging coupler stem, of a coupler head pivotally mounted on said stem, a lever device mounted upon said stem, and a spring located between said lever device and said head 10 and adapted to be energized both by a displacement of said lever device from normal position and by a displacement of said head with respect to said stem, said head when displaced laterally in either direction from 15 normal position with respect to said stem being adapted to move one end of said spring to energize the same, and said lever device being adapted to cause the movement of the other end of said spring when said 20 stem is rotated in either direction from normal position.

6. In a draft appliance for railway vehicles, the combination with a laterally swinging coupler having a head and stem, of a lever 30 device mounted on said stem and adapted to turn with respect thereto, and means extending in the direction of length of said stem for yieldingly resisting movement of said lever device, said lever device having a 35 plurality of forwardly extending arms each of which is adapted to engage the railway vehicle at a point between the coupler head and the point about which such arm turns.

7. In a draft appliance for railway vehicles, the combination with a laterally swinging coupler stem and a head pivotally mounted on said stem, of a lever device mounted on said stem and adapted to turn with respect thereto, means for yieldingly 40 resisting movement of said lever device with respect to said stem, said means being located between said lever device and said head, and means movable independently of said lever device for rotating said head to 45 normal position with respect to said stem.

8. In a draft appliance for railway vehicles, the combination with a laterally swinging coupler stem, of the following instrumentalities mounted on said stem in orderly 55 arrangement, to wit, a pivoted coupler head, a reciprocating follower, a spring, another follower, and means for actuating said last named follower.

9. In a draft appliance for railway vehicles, the combination with a laterally swinging coupler having a head and stem, of a lever device having a plurality of fulcra adapted to engage corresponding fulcrum points on said stem and having a plurality 60 of arms adapted to engage the railway vehicle 65

cle in advance of the said fulcra, and spring means for resisting movement of said lever device with respect to said stem, said spring means being located between the coupler head and said lever device.

70

10. In a draft appliance for railway vehicles, the combination with a laterally swinging coupler having a head and stem, of the following instrumentalities mounted on said stem in orderly arrangement rearwardly, to wit, a spring, a follower, and a lever device which is adapted to turn with respect to said stem.

75

11. In a draft appliance for railway vehicles, the combination with a laterally swinging coupler stem and a head pivotally mounted on said stem, of a lever device fulcruming on said stem, a spring for yieldingly resisting displacement of said lever device from normal position and for yieldingly resisting displacement of said head from normal position with respect to said stem, a follower interposed between said spring and said lever device, and a follower interposed between said spring and said head, said followers having engaging portions whereby one of them serves to guide the other.

80

12. In a draft appliance for railway vehicles, the combination with a laterally swinging coupler having a head and stem, of a follower slidably mounted on said stem, a rigid lever device movably mounted on said stem and engaging said follower, and a spring adapted to be actuated through said follower by said lever device, said follower and said lever device having engaging portions forming a rocking bearing.

85

13. In a draft appliance for railway vehicles, the combination with a laterally swinging coupler having a head and stem, of a spring mounted on said stem, a lever device mounted on said stem, and a follower interposed between said spring and lever device adapted to cause said spring to be energized when said stem is displaced laterally from normal position, said lever device having a plurality of arms and pintles engaging said follower intermediate of the ends of said arms.

90

14. In a draft appliance for railway vehicles, the combination with a laterally swinging coupler stem and a head pivotally mounted on said stem, of a follower mounted on said stem and engaging said head and adapted to be actuated by said head, said follower having longitudinally extending portions and a plurality of transversely extending portions connecting said longitudinally extending portions at different points, a spring seated upon said follower and located in the space between the transversely extending portions thereof, another follower bearing against said spring, and means for actuating said last named fol- 120 125 130

lower to energize said spring when the coupler stem is displaced laterally from its normal position.

15. In a draft appliance for railway vehicles, the combination with a laterally swinging coupler stem and a head pivotally mounted on said stem, of a follower mounted on said stem and engaging said head and adapted to be actuated by said head, a 10 spring adapted to be energized by said follower when said head is displaced laterally from normal position with respect to said stem, and means for energizing said spring when the said stem is displaced laterally 15 from normal position, said means involving a lever device which is mounted on said stem and is movable with respect to said stem and another follower having a rocking bearing on said lever device.

20 16. In a draft appliance for railway vehicles, the combination with a laterally swinging coupler having a head and stem, of a lever device mounted on said stem and adapted to turn upon a plurality of fulcrum 25 points carried by said laterally swinging stem, and a spring which is energized by the turning movement of said lever device on either of said fulcrum points when the coupler stem is displaced laterally from its normal 30 position, said spring and the fulcrum points carried by said stem being on opposite sides of said lever device.

17. In a draft appliance for railway vehicles, the combination with a laterally 35 swinging coupler stem and a head pivotally mounted on said stem, of a spring, means whereby the pivotal displacement of said head from normal position with respect to said stem causes said spring to be 40 energized, and means whereby the lateral

displacement of said stem from normal position causes said spring to be energized, said means last named involving a lever device having a plurality of fulcra, said fulcra and said spring being upon opposite sides 45 of said lever device.

18. In a draft appliance for railway vehicles, the combination with a laterally swinging coupler stem and a head pivotally mounted on said stem, of a spring mounted 50 on said stem and extending in the direction of length thereof, means whereby the displacement of said head from normal position with respect to said stem causes said spring to be energized, and a lever device 55 actuated by the lateral displacement of said stem for energizing said spring, said head and said spring both being on the same side of said lever device.

19. In a draft appliance for railway vehicles, the combination with a laterally swinging coupler stem and a coupler head pivotally mounted thereon, of a lever device mounted on said stem, and a spring adapted to be energized by said lever device 60 upon a lateral swinging movement of said stem and also adapted to be energized independently of said lever device by a pivotal movement of said head with respect to said stem, said lever device having a 65 plurality of arms adapted to have pivotal movement with respect to said stem, and each of said arms extending forwardly from its point of pivotal movement toward said coupler head and being adapted to engage 70 a stationary part of the car.

In testimony whereof we affix our signatures.

EDWIN L. BRADFORD.
GILBERT P. RITTER.
